UNITED STATES PATENT OFFICE.

WILLIAM H. WASHBURNE, OF CHICAGO, ILLINOIS, ASSIGNOR, BY MESNE ASSIGNMENTS, TO MOTOR VALVES, INC., OF WOODSTOCK, ILLINOIS, A CORPORATION OF DELAWARE.

METHOD OF MAKING TWO-PIECE VALVES.

Application filed March 10, 1924, Serial No. 698,145. Renewed September 10, 1927.

In my prior application, Serial No. 509-948, filed October 24, 1921, I have disclosed a novel process by means of which a head may be forged on the end of a finished valve stem, 5 producing a product which requires only the grinding of the valve face on the head in order completely to finish the valve. In carrying out my aforesaid process I employ a washer-like blank, the hole in which is 10 somewhat larger in diameter than the stem; the heated blank being pressed into the shape of a valve head while surrounding the cold stem. During the forging or pressing operation the metal toward the top of the 15 blank, if the hole in the blank is cylindrical, comes in contact with the valve stem before the lower portion of the hole in the blank is closed sufficiently to bring about contact between the stem and the metal near the bottom 20 of the blank, and heavy pressure is required to bring about the complete closing of the lower end of the hole in the blank. It sometimes occurs, in the manufacture of valves having small stems, that the pressure 25 required to insure perfect contact between the metal near the underside of the head and the stem is so great that the stem will be damaged and, at times, cut completely in two. This difficulty may be ameliorated 30 somewhat by making the hole in the blank in the shape of a frustum of a cone, the larger end being at the top; but it is not feasible, by a simple punching operation, to secure the necessary taper to the hole to 35 avoid the danger of injury to the valve stems in the process of manufacturing valves having very small stems. Since the most important advantage of the aforesaid process lies in the cheapness with which finished 40 valves can be made, it is not desirable to add to the expense of manufacture by drilling or reaming a conical hole in the blank.

Furthermore, while the foregoing difficulties do not seem to be encountered in the 45 manufacture of valves except those having very small stems, it is desirable, in some cases, to be able to reduce to a minimum the amount of working of the metal in the blank for the head during the step of attaching the 50 head to the finished valve stem. This end can be attained by giving the blank as nearly as may be the shape of a finished head,

before it is applied to the stem. This can conveniently be accomplished by forging the head about a mandrel in the same dies that are employed to attach the head to the stem. The mandrel may be made tapered so that when it is withdrawn from the forged blank it will leave a hole of the proper shape to give the best results when the head is forged upon the stem. Consequently, two useful results may be obtained, at a very small expense, by a simple preliminary forging step. 55

My invention may therefore be said to have for its object to produce a simple and novel improvement in the process of manufacturing two-piece valves, which consists in properly shaping the hole in the blank or in preforming the blank so that it will have substantially the shape of a finished head, or 60 65 both, by a simple forging operation. 70

Viewed in another of its aspects, my invention may be said to have for its object to improve the process of forging a head on a finished valve stem by using the same dies, 75 first to preshape the blank, and then to work it only sufficiently to close the hole therein upon the valve stem.

The various features of novelty whereby my invention is characterized will herein- 80 after be pointed out with particularity in the claims; but for a full understanding of my invention and of its objects and advantages, reference may be had to the following detailed description taken in connection with 85 the accompanying drawing, wherein:

Figure 1 is a vertical section through a pair of dies in the act of closing upon a blank for the purpose of preshaping it; Fig. 2 is a view similar to Fig. 1 showing the dies closed on the blank; Fig. 3 is a view similar to Fig. 1, showing a valve stem in the lower die, with the preformed blank surrounding the upper end of the same and the mandrel removed from the upper die; and Fig. 4 is a view similar to Fig. 3, showing the dies closed on the blank so as firmly to unite it to the stem. 90 95 100

Referring to the drawing, 1 and 2 represent respectively a lower and an upper die, the lower die having therein a cavity 3 of the exact size and shape of the valve head to be produced. The die cavity forms the bottom of a chamber 4 into which the upper

die is adapted to descend during the forging operation. The lower die has an opening or passage extending downwardly through the same from the center of the die cavity; 5 this bore or passage being of the proper diameter to cause a finished ground valve stem to be a sliding fit therein. The upper die has in the under side thereof a pocket or recess 6 somewhat larger in diameter than 10 the passage 4, for the purpose of providing a clearance between the upper die and the upper end of a valve stem during the operation of forging a head on the stem.

When the dies are used to forge a blank to 15 produce a preformed valve head, a mandrel or plunger 7 is inserted in the recess 6; the projecting portion of the mandrel or plunger comprising a lower section 8 that will fit into the bore or passage 5, and an upper 20 conical section 9. The parts are so proportioned that when the dies are closed on a blank such as indicated at A in Fig. 1, they forge it into the shape of a finished head, as indicated at B in Fig. 2, excepting only that 25 the hole in the center of the blank will have the shape of the conical section of a mandrel.

When the blank has to be attached to a stem, the mandrel is removed from the upper die, the stem C is inserted in the bore or 30 passage 5 in the lower blank, and the pre-formed head, heated to a suitable temperature, is dropped into the die cavity so as to surround that portion of the stem which projects into the cavity, as illustrated in 35 Fig. 3. The stem may rest at its lower end upon a suitable block 10 yieldably supported upon a spring 11 which may be adjusted by means of a vertically adjustable plug 12 in the lower end of the lower die. By this 40 means the stem may be yieldably supported so as to project just the proper distance into the die cavity. The dies are then closed to bring about the condition illustrated in Fig. 4, in which the under surface of the head 45 retains the shape given by the first operation of forging the initial blank, while the thickness will have been slightly reduced to cause the metal of the blank to flow inwardly into intimate contact with the stem. In 50 Fig. 4 the stem is indicated at C and the head at D. At the end of the forging step illustrated in Fig. 4, the complete valve is removed from the dies and the head cooled before the stem is given an opportunity to 55 become objectionably heated.

The upper end of the stem will usually be provided with one or more transverse external shoulders, conveniently produced by cutting one or more annular grooves into the 60 stem, as indicated at 14; so that during the final forging operation the metal of the head enters the grooves and mechanically interlocks the head and the stem.

It will be seen that the lower end of the 65 hole in the pre-shaped head may have sub-

stantially the same diameter as the stem, so that in the final forging operation the metal adjacent to the under face of the valve will receive little or no working, the closing of the hole being caused by a slight downward 70 and inward movement of the metal in the upper portions of the valve. In the drawing I have exaggerated the size of the conical hole in order to make the principle of my invention clear; but, in actual practice, since 75 the work of making the pre-shaped head may be done very accurately, the taper and the clearance will be slight.

While I have illustrated and described with particularity only a single preferred 80 form of my invention, I do not desire to be limited to the exact structural details thus illustrated and described; but intend to cover all forms and arrangements which come within the terms employed in the definitions of my invention constituting the appended claims.

I claim:

1. The method of making a two-piece valve which consists in forging a blank to 90 give it the shape of a valve head having a central hole therethrough slightly larger in diameter than a stem to which the head is to be applied, and then forging the head upon a stem in such a manner that the material of the head is closed upon the stem without exerting any forging pressure on the stem in the direction of its length.

2. The method of making a two-piece valve which consists in forging a blank in 95 dies to give it the shape of a valve head having a central hole slightly larger than a stem to which the head is to be applied, and then placing a stem in said hole and forging the head in the aforesaid dies to unite the 100 head and the stem.

3. The method of making a two-piece valve which consists in forging a blank in 105 dies about a mandrel to give it the shape of a finished valve head but of a slightly greater thickness than the latter and having a central hole therethrough slightly larger than a stem, removing the mandrel and substituting therefor a valve stem, and then again forging the head in the aforesaid dies 110 to unite the head to the stem.

4. The method of making a two-piece valve which consists in forging a blank to 120 give it the shape of a valve head having a central hole therethrough increasing somewhat in diameter from the bottom toward the top, inserting a valve stem into said hole, and then forging the blank by pressure exerted solely on the blank, while the stem is left free from any forging pressure in the direction of its length, to unite the head to the stem.

5. The method of making a two-piece valve which consists in forging a blank to 125 give it the shape of a valve head having a 130

central hole of approximately the same diameter at its lower end as the diameter of a stem to which the head is to be attached and increasing gradually in diameter toward the

⁵ top, inserting a valve stem into said hole, and then forging the head by a pressure exerted solely on the same, while the stem is

left free from any forging pressure in the direction of its length, to cause the metal of the head to flow inwardly into intimate contact with the stem. 10

In testimony whereof, I sign this specification.

WILLIAM H. WASHBURNE.
